ELECTRICALLY-OPERATED AUDIBLE SIGNAL DEVICE

James R. Putnam, Waterbury, Conn., assignor to Waterbury Clock Company, Waterbury, Conn., a corporation

Application May 8, 1931, Serial No. 535,833

4 Claims. (Cl. 177—7)

This invention relates to an improvement in electrically-operated audible-signal devices, such as electric bells, buzzers, etc., and particularly to audible-signal devices of the type designed primarily for operation by alternating electric current.

The main object of this invention is to provide, at a low cost for manufacture, a simple, reliable and effective electric audible-signal device capable of being operated preferably by alternating electric current.

With the above and other objects in view as will appear from the following, my invention consists in an electrically-operated audible-signal device characterized by electromagnetic means for producing a pulsating magnetic flux in consonance with an alternating electric current; a hammer or striker vibrating in response to the said pulsating magnetic flux; and a sounding-member, such as a bell or gong, made of magnetic material; the elements referred to being constructed and arranged so that a magnetic circuit is provided in which the said sounding-member and the said striker form links respectively.

My invention further consists in an electrically-operated audible-signal device characterized as above and having certain other details of construction and combinations of parts as will be hereinafter more particularly described and claimed.

In the accompanying drawing:

Fig. 1 is a view in side elevation of one form which an electrically-operated audible-signal constructed in accordance with my invention may assume;

Fig. 2 is a side view thereof but viewing the device from a right angle to the position in which it is shown in Fig. 1;

Fig. 3 is a top or plan view thereof; and

Fig. 4 is a central longitudinal sectional view taken on the line 4—4 of Fig. 3.

The particular electrically-operated audible-signal device herein chosen for the illustration of my invention comprises, as shown, an electric coil or solenoid 10 having end-flanges 11 and 12 formed of insulating material and respectively located at its opposite ends.

Extending axially through the coil 10 just referred to is a core 13 of iron, or other suitable magnetic material, the lower end of which extends through the horizontal arm 14 of an L-shaped bracket 15, also of magnetic material, and over the underface of which its terminal 16 is riveted.

The coil 10 is retained in place upon the core 13 by bearing at its lower end against the upper surface of the arm 14 of the bracket 15, in which position it is held by a retaining-washer or ring 17 bearing against the upperface of its top-flange 11, as clearly shown in Fig. 4.

The core 13 extends slightly above the coil 10 to form a supporting-stud 18 having a conical upper terminal 19 upon which rests the sounding-member, preferably a concavo-convex bell 10 or gong 20 formed of magnetic material and having the upper end of the coil 10 and its core 13 extending within its hollow underface.

The upper end of the core 13 is formed with an upwardly-opening axial bore 21 into which is threaded the lower end of a screw 22 extending through the bell or gong 20 and serving to firmly anchor the same in place.

The L-shaped bracket 15, in addition to the horizontal arm 14 already referred to, is provided also with a depending arm 23 to the outer face of which is secured by means of rivets 24 and 25 the lower end of a flat sheet-metal spring 26 which extends upwardly beyond the said bracket and has secured to the inner face of its upper end an armature-like hammer or striker 27, preferably of rectangular shape and formed, preferably, of relatively-heavy sheet-iron.

The sheet-metal spring 26 is preferably formed of steel or other magnetic material and has the hammer or striker 27 just referred to secured to its upper end by means of rivets 28 and 29, the upper one of which latter is preferably made of non-magnetic material and is arranged in position to engage the outer surface of the rim of the bell or gong 20 as the hammer is vibrated. The employment of a non-magnetic rivet, such as 28, to engage the bell or gong as described, serves to prevent the sticking of the hammer to the said bell.

When the leads 30 and 31 of the coil 10 are connected to a source of alternating current, such as a commercial alternating-current system, a pulsating magnetic flux will be set up by the said coil, which flux will include in its path of travel and will flow through the core 13, bell 20, striker 27, spring 26 and bracket 15, and thence back to the core. It being understood, of course, that when the coil 10 is energized by an alternating current, the magnetic flux will first flow in one direction and then in another, with the result that the striker or hammer 27 forming a link in the magnetic path will be vibrated back and forth to strike the bell 20.

Preferably, the spring 26 which forms a resil-

ient mount for the hammer or striker 27, will be so related in its tension to the mass of the said striker that its period of vibration will be substantially harmonic to the pulsations of the 5 magnetic flux generated by the current flowing through the coil 10.

By so constructing and arranging the parts of my improved device so that the bell, or other sounding-member, provides a path for the magnetic flux which vibrates the armature-like 10 striker 27, or other suitable member, I have succeeded in producing an audible-signal which will operate satisfactorily in response to relatively-high-frequency alternating current, such as sixty-cycle current, with the minimum expenditure 15 of electrical energy.

It will be understood by those skilled in the art that my invention may assume varied physical forms without departing from my inventive 20 concept, and I, therefore, do not limit myself to the specific embodiment herein chosen for illustration, but only as hereinafter claimed.

I claim:

1. In an alternating-current electrically-operated 25 audible-signal device, a fixedly-mounted electromagnet having a core and a winding, a sounding-member of magnetic material carried by and magnetically connected with one end of said core, a resiliently-mounted vibratory striker 30 of magnetic material, and a bracket of magnetic material magnetically connected to the opposite end of said core and to the said resiliently-mounted striker to provide a magnetic connection 35 between said core and striker, the winding of said electromagnet designed and adapted to be connected with a source of alternating electric current, whereby a magnetic flux is produced in said sounding-member responsive to the pulsations of said current to impart vibratory striking movement to said striker with respect to said sounding-member.

2. In an alternating-current electrically-operated 40 audible-signal device, a fixedly-mounted

electromagnet having a core and a winding, a sounding-member of magnetic material fixedly carried by and magnetically connected with one end of said core, a bracket of magnetic material magnetically connected to the opposite end of 5 said core, a resilient member of magnetic material connected to said bracket, and a vibratory striker of magnetic material connected to said resilient member and extending a major portion of the distance between said bracket and said 10 sounding-member.

3. In an alternating-current electrically-operated 15 audible-signal device, a fixedly-mounted electromagnet having a core and a winding, a sounding-member of magnetic material fixedly carried by and magnetically connected with one 20 end of said core, an L-shaped bracket of magnetic material having one arm magnetically connected to the opposite end of said core and having the other end extending away from said sounding member, a resilient member connected to the other arm of said bracket, and a vibratory striker of magnetic material connected to said resilient member and extending a major portion of the distance between said bracket and 25 said sounding-member.

4. In an alternating-current electrically-operated 30 audible-signal device, a fixedly-mounted electromagnet having a core and a winding, a sounding-member of magnetic material fixedly carried by and magnetically connected with one 35 end of said core, a bracket of magnetic material magnetically connected to the opposite end of said core, a resilient member of magnetic material connected to said bracket, and a vibratory 40 striker of magnetic material connected to said resilient member by means including a non-magnetic rivet positioned to engage said sounding-member and prevent direct contact of the magnetic material of said vibratory striker with said sounding-member.

JAMES R. PUTNAM.
